UNITED STATES PATENT OFFICE.

HARRY WALLACE LAWRENCE, OF DENVER, COLORADO.

COMBINED BOX AND SOCKET FOR ELECTRIC LAMPS.

966,026.

Specification of Letters Patent.

Patented Aug. 2, 1910.

Application filed January 17, 1910. Serial No. 538,568.

To all whom it may concern:

Be it known that I, HARRY W. LAWRENCE, a citizen of the United States of America, residing in the city and county of Denver 5 and State of Colorado, have invented a new and useful Combined Box and Socket for Electric Lamps, of which the following is a specification.

My invention relates to improvements in the coöperative electric lamp socket holding boxes that are adapted to support the lamp sockets and the ends of the electric circuit wires and their incasing tubes on the ceilings, walls and other parts of buildings, and 10 the objects of my invention are: First—to provide a simple and practical combined box and socket fixture for lamp circuits. Second—to provide a combined wall and ceiling box and socket that comprises a simple, shallow, disk shaped fixture that is quickly and easily connected to a pipe inclosing circuit wire system and that presents a neat and attractive appearance to the eye; and third—to provide a combined wall and 15 ceiling lamp holding fixture that comprises a box adapted to connect to wire incasing tubes or pipes and to receive the circuit wires from said pipes, and that is adapted to receive an operative lamp socket and in which 20 the socket is arranged to be removably secured to the box and is arranged therein against rotative movement. I attain these objects by the mechanism illustrated and 25 described in the accompanying drawings, in 30 which—

Figure 1 is a view illustrating the application of the improved device. Fig. 2 is a plan view of the box and socket, the lamp being removed. Fig. 3 is a similar view, 35 the cap which is screwed upon the socket being removed. Fig. 4 is a plan view of the box, the socket being removed. Fig. 5 is a bottom view of the socket. Fig. 6 is a side view of the socket. Fig. 7 is a sectional view—full size—on the line 7—7 of Fig. 2; and Fig. 8 is a sectional view—full size—on the line 8—8 of Fig. 2.

Similar characters of reference refer to similar parts throughout the several views.

In the present state of the art of wiring buildings for electric lights the best practice calls for the incasement of the circuit wires in tubes and of the electric lamp holding sockets in receptacles called boxes. The tubes 50 used may consist of any suitable material or metal, iron piping being used extensively, and

an electric lamp wiring and socket system is installed on the ceilings and walls of buildings substantially as illustrated in Fig. 1, in which the numeral 1 designates the circuit wire incasing piping, 2 and 2^A designate the circuit wires incased thereby, 3 designates the lamp holding sockets and 4 the boxes that incase the socket and support the terminal end of the circuit wires. 65

My improved coöperating lamp socket and circuit wire terminals incasing box is adapted to provide a compact and easily connecting and disconnecting electric wiring and lamp supporting socket and fitting that 70 is small in diameter and narrow in thickness and consequently presents a neat appearance on the wall or ceiling of a room.

In my coöperating socket and box, the socket is preferably made of porcelain, and 75 the box is made of metal or other suitable material, but preferably cast iron. The box consists of a cylindrical shell portion 5, provided with a bottom or base portion 6. One or two projecting hub portions 7 and 8 project from the side of the box, depending on whether the box is to be used for a lamp at the terminal end of a circuit or is to be inserted in a circuit or line intermediate of its 80 ends, and the box is illustrated in Fig. 1 85 with one and also with two connecting hub portions. These hub portions are adapted to be threaded connected to the ends of the circuit wire incasing tubes 1.

When the boxes are provided with two 90 hubs, they are preferably positioned on diametrically opposite sides of the box, but if a lamp is desired at the apex of an angular turn in a circuit wire one hub can be placed 95 at right angles or at any other desired angle to the axial direction of the opposite hub, as shown in Fig. 4.

On the inside surface of the bottom of the box and on the inside of the side of the shell of the box two lugs 9 are formed, which 100 are positioned on opposite sides of the inside of the box and preferably in alinement with the longitudinal axis of the tube connecting hub portion or portions of the box. These lugs are short pointed lugs that are 105 cast integral with the side and bottom portion of the box, and they project into recesses 10 that are formed in the bottom edge of the base portion 11 of the lamp socket. This base portion of the socket also forms its 110 main body portion and it is preferably made enough smaller in diameter than the aper-

ture in the box to leave a clear space all around it when it is placed centrally in it, and the lugs 9 extending into the recesses 10 of the base at its opposite sides hold it centrally in the box and at the same time prevent the socket from turning rotatively in the box. It is necessary, however, to secure the socket to the box, and while this feature of my invention may be carried out in several different ways and my invention contemplates any suitable method of securing the socket to the box against displacement, I preferably carry out this feature of my invention in the following manner: The base 11 of the socket is in the form of a flange, which projects from the main or body portion 12, and this flange, adjacent to the recesses 10, is of the same thickness as the lugs 9, but the flange increases in thickness or slopes from the recesses 10 to diametrically opposite points on the body 12, as shown in Fig. 6. The ends of the body 12, adjacent to the recesses 10, are recessed as shown at 12^A, Fig. 3, and swinging buttons 13 are secured to the tops of the lugs 9 by screws 14, and these buttons are arranged to swing over onto the flange 11 and project into the recesses 12^A and be clamped down upon the flange and the lugs 9 by the screws 14, thus securing the base portion of the socket firmly but removably to the bottom of the inside of the box.

The thickest portions 15 of the flange form diametrically opposite flat bearings 16 and 17 for a pair of contact terminal strips 18 and 19, the inner ends of which extend into recesses 18^A and 19^A respectively, which extend from the top of the body of the socket to the level of the bearing surfaces 16 and 17. These terminal contact strips are provided with binding screws 20 and 21. These raised bearing portions and the contact terminal strips and their binding screws are preferably placed at right angles to the recesses 10 in the base and on the outside of the base and diametrically opposite to each other, in which position they are accessible from the front of the socket and box, and this arrangement enables the binding screws to be easily manipulated to secure the circuit wires to or release them from the contact terminal strips, as will be hereinafter fully described.

The central portion of the socket is provided with an axial aperture 22 which extends into it from its upper or top side, in which an interior and also an exterior threaded conductive receiving shell 24 is placed, which is commonly called the receiver, into which the lamp is screwed. This receiver is provided with three outwardly extending feet 25, 26 and 27. The foot 25 forms a contact terminal conductor for the receiver shell and extends into the recess 18^A and is clamped beneath the contact terminal

18 that conducts the electric current from the terminal end of the circuit wire 2, to and through the receiver to the lamp. The conductor 18 is clamped upon the foot 25 by a screw 25^A, which extends up through a hole 70 in the socket and enters a threaded hole in the said foot. The head of the screw is housed in a recess 25^B in the base of the socket. The other two feet 26 and 27 of the receiver are housed in recesses 28 formed in the top of the socket and are secured therein by screws 29, which extend down through holes formed in the socket and receive nuts 30, which are housed in recesses 31 in the base of the socket. 80

The contact terminal strip 19 extends from its raised bearing 17 down through the recess 19^A in the body of the socket to the bottom of the axial recess 22 in the socket, and then extends inwardly beyond the center of the aperture and forms a contact terminal for the center of the end of the threaded plug of an electric lamp. A recess 32 is formed in the receiver shell above the contact terminal strip 19 to prevent a short circuit between the receiver shell and the said strip 19. A cap 33 is threaded to the outside threaded portion of the receiver shell to screw down against the top of the body of the socket. The combined thicknesses 90 of the base portion of the socket and of the outer edge of the cap are equal to the depth of the box, which being but about an inch in depth by about three inches in diameter presents a neat appearance when on a wall 100 or ceiling. 95

The axial aperture in the socket permits the plug end of the lamp to screw down through the receiver shell and engage the contact terminal strip 19 with its end, and the receiver shell is made long enough to entirely cover the threaded portion of the plug end of the electric lamp, which insures the largest area of current conductive surface possible between the lamp and the receiver shell. This feature of my invention, as well as the receiver itself, as shown and described, and the contact terminals, in substantially the form and arrangement herein illustrated and described, are disclosed in application for patent granted to me August 27, 1907, Serial Number 864,427; also applications, Serial Number 445,149, filed July 24, 1908, and Serial Number 502,145, filed July 16, 1909, and now pending. 110 115

The operation is as follows: The box is secured to the end of a circuit wire covering tube or pipe and the circuit wires are extended through the hub of the box into its interior. The socket with its cap removed is then placed in the box with its recesses 10 fitting around the lugs 9, and the clamping buttons 13 are turned on the clamping screws 14 to rest on the lugs and also on top of the flange portion of the socket. The 120 125 130

clamping screws are then turned to clamp the buttons down against the lugs and the flange, thus removably securing the socket to the inside of the box against accidental displacement. The ends of the circuit wires are then secured to both of the contact terminal strips by the binding screws 20 and 21, which are so positioned that a screw driver can be applied to them from the front side 10 of the box. The cap is then screwed onto the receiver shell and acts as a cover for the wire connections and gives a finished appearance to the box. A lamp is then screwed into the receiver of the socket, until its end 15 contacts with the conductor 19.

Having described my invention, what I claim as new and desire to secure by Letters Patent is:

1. In a combined wall and ceiling box and 20 socket for electric lamps, the combination of an operative electric lamp holding socket provided with recesses at its opposite ends and with binding posts and terminal strips on its sides with a box arranged to surround 25 said socket provided with circuit wire entrance apertures leading to said socket's binding posts, lug portions in said box fitting into the recesses of said socket, a binding screw threaded to each of said lugs and 30 a button loosely mounted on said screw and arranged to be clamped to said lugs and onto said socket, and means for connecting said box to circuit wire housing tubes or pipes.

2. In a combined wall and ceiling box and 35 socket for lamps, the combination of the circuit wires, the circuit wire incasing pipes, and an operative electric lamp socket provided with binding posts and contact terminal strips arranged therein to conduct- 40 ively connect with a lamp and arranged on the opposite sides of said socket in a position to be manipulated from the lamp receiving end of said socket, a threaded receiver shell in said socket adapted to receive 45 a lamp, and a cap threaded to said receiver shell, with a disk shaped box of any suitable material arranged to surround said socket, means including a clamping device attached to said box for removably securing said 50 socket in said box, said box being provided with a hollow hub or with hollow hubs arranged and adapted to permit said circuit wires to be inserted into said box to the binding posts' contact terminals of said

socket, said hollow hub portions of said box 55 being provided with threads adapted to connect said box to said circuit wire incasing tubes or pipes.

3. A combined wall and ceiling box and 60 socket for electric lamps comprising an open top disk shaped box adapted to be connected to wire holding tubes or pipes and arranged to receive circuit wires and provided with a pair of oppositely arranged lug portions, provided with a clamping 65 screw, and a swinging locking button loosely mounted on said screw, with an operative lamp holding socket comprising a base portion provided with oppositely arranged flanged portions provided with recesses fitting loosely over the lug portions of said box, said flange portions being adapted to receive said button, said button being adapted to be clamped against the said flanged portions of said base and the lug portions 70 of said box by said screw, and suitable circuit wire operative binding posts and contact terminal strips on said base portion of socket arranged to secure the ends of circuit wires to said socket, a threaded electric lamp 80 receiving shell secured to said base and arranged to receive the threaded end of an electric lamp in circuit relation to said contact terminal strips, and a cap threaded to said shell and fitting in the top portion of 85 said box.

4. In a device as specified, the combination with a lamp socket, having oppositely arranged recesses in its base, of a box for 90 said socket having lugs which extend into said recesses and clamping devices on said lugs for holding said socket in said box; a pipe extending into said box; a metal lamp receiver in said socket; conductors upon the 95 socket, one of which connects with the lamp receiver, while the other is adapted to be engaged by the contact end of a lamp; binding screws in said conductors and a cap for closing the box, said cap having a central aperture through which the lamp receiver 100 passes.

In testimony whereof I affix my signature in presence of two witnesses.

HARRY WALLACE LAWRENCE.
